UNITED STATES PATENT OFFICE.

DARIUS A. STEININGER, OF LAPORTE, INDIANA.

PRIMER FOR INTERNAL-COMBUSTION ENGINES.

1,221,620.

Specification of Letters Patent.

Patented Apr. 3, 1917.

Application filed August 6, 1914. Serial No. 855,488.

To all whom it may concern:

Be it known that I, DARIUS A. STEININGER, a citizen of the United States, residing at Laporte, in the county of Laporte and 5 State of Indiana, have invented new and useful Improvements in Primers for Internal-Combustion Engines, of which the following is a specification.

This invention relates to primers for internal combustion engines, the object in view 10 being to produce a device of the nature referred to which is adapted to be used in connection with any engine of the character noted for the purpose of insuring and 15 rendering easy and safe the starting of the engine, the device being particularly valuable and efficient in cold weather and at other times when it is a matter of difficulty to prime and start an internal combustion 20 engine with the aid of the ordinary carbureter.

The invention hereinafter described is in 25 the nature of an improvement upon the construction disclosed in my pending application Serial No. 829,608 filed April 4, 1914, means being employed for diverting or deflecting a portion of the compressed air passing through the main conduit and carrying said air into the bowl containing the priming agent, whereby a greater pressure is obtained in said bowl and the priming agent 30 more effectively sprayed into the main conduit from whence it is forced under pressure and intermingled with the compressed 35 air, into the combustion chamber or chambers of the cylinder or cylinders of the engine.

With the above and other objects in view, 40 the invention consists in the novel construction, combination and arrangement of parts, as herein described, illustrated and claimed.

In the accompanying drawings:—

Figure 1 is a plan view of the priming device of this invention.

Fig. 2 is a central vertical longitudinal section through the same.

Fig. 3 is an end view thereof looking toward the discharge end of the priming device.

The primer contemplated in this invention embodies a main conduit 1 preferably in the form of a pipe or tube having an entrance elbow 2 adapted to have a compressed air connection attached thereto, said elbow being shown as threaded at 3 for that

purpose. The elbow contains an internal valve seat 4 in conjunction with which works a compressed air admission valve. The stem of this valve extends through a 60 guide opening 6 in the top wall of the main conduit and said stem indicated at 7 has a jointed connection at 8 with the valve operating means which is shown in the form of a lever 9 one end of which is pivotally connected at 10 to an oscillatory fulcrum post 11 pivotally connected at 12 to a lug on the outside of the conduit 1. A coiled expansion spring 14 is interposed between a boss 15 on the conduit 1 and a flanged collar 16 65 on the stem 7, said spring acting to hold the admission valve normally closed. By pressing on the lever 9, the operator may unseat the admission valve and permit the air under pressure from any storage tank or 70 source of supply to enter the conduit 1. 75

Below the main conduit 1 and preferably formed integrally therewith is a cup 17 adapted to contain a priming agent of any kind such, for example, as gasolene, the 80 priming agent being introduced into said cup through a filling opening 18 normally closed by means of a filler plug 19. 20 designates a primer intake tube extending vertically from the main conduit 1 downwardly 85 within the cup 17 and terminating above the bottom of the cup as shown in Fig. 2. The bore 21 of said tube terminates at its point of junction with the interior of the conduit 1 in a valve seat 22. In conjunction with the valve seat 22 I employ a regulating valve 23 shown in the form of a needle valve which is threaded through and adjustable in a boss 24 extending upwardly from the top of the conduit 1. The needle valve is provided 90 with an operating head 25 by means of which it may be adjusted.

The main conduit 1 is provided along the upper side and one of the side walls thereof with an extension 26 in which is formed a compressed air passage 27, said passage communicating at its receiving end with the conduit 1 near the top of the latter and extending therefrom into the top of the cup 17 so as to carry the air pressure into said cup 100 above the priming agent. In rear of the receiving end of the passage 27 there is arranged a deflector 28 shown in the form of a plate, lip or web projecting from the top of the conduit 1 toward the bottom thereof any 105 suitable distance, said deflector serving to divert a portion of the compressed air as it

enters the main conduit and direct the same through the passage 27 into the cup 17. The passage 27 is of sufficient area in cross section to cause an excess of pressure of air 5 therein over the air pressure around the regulating valve 23. This insures the forcing of the priming agent from the cup 17 upwardly through the bore 21 and into the main conduit 1, said priming agent being 10 sprayed or spread by the valve 23 and scattered throughout the conduit 1 where it is taken up by the onrushing air and carried with and by the compressed air into the combustion chamber of the engine cylinder. 15 The discharge end of the conduit 1 is threaded as shown at 29 to receive a suitable pipe connection (not shown) to the engine, which connection is ordinarily fitted with a back pressure check valve (also not shown). 20 The operation of the primer may be described as follows. With the piston of the engine cylinder in firing position, the admission valve is opened. The inrushing air under pressure passes through the conduit 1, a 25 portion thereof being deflected by the member 28 and directed through the passage 27 into the cup 17. This pressure forces some of the priming agent past the regulating valve 23 into the conduit 1 where it is taken up and carried by the compressed air into 30 the combustion chamber of the engine. Sufficient air passing into said combustion chamber to insure a proper explosive mixture under pressure. The admission valve 35 being then closed, a spark is generated in the combustion chamber, exploding the mixture

and starting the engine. By arranging the passage 27 and the deflector 28 in the manner shown and described, engines ranging from very small to very large H. P. may be started with the same priming device or rather with a priming device of the same size thus doing away with the necessity of carrying a large number of different sizes in stock. 40

What I claim is:—

In a primer for internal combustion engines, a compressed air conduit, a spring seated admission valve for said conduit, a bowl located below said conduit and extended laterally to the side of the conduit where 45 it is provided with a filling orifice adapting it to be filled with a priming agent, a regulating valve the stem of which extends diametrically and downwardly through said conduit and is operable from above the top 50 thereof for admitting the priming agent from said bowl to said conduit, said valve having a conical face acting to spread the priming agent, the primer being formed with a passage leading from the upper portion 55 of said conduit into the upper portion of said bowl, a stationary deflector arranged back of the entrance to said passage and obstructing only the upper portion of said conduit, and means for opening said admission 60 valve.

In testimony whereof I affix my signature in presence of two witnesses.

DARIUS A. STEININGER.
